YORK.

PULL-SOCKET.

1,122,031.

Specification of Letters Patent. Patented Dec. 22, 1914.

Application filed July 6, 1912. Serial No. 708,123.

To all whom it may concern:

Be it known that we, HOWARD R. SARGENT and THEODORE KOCH, citizens of the United States, residing at Schenectady, county of 5 Schenectady, State of New York, have invented certain new and useful Improvements in Pull-Sockets, of which the following is a specification.

The present invention relates to sockets 10 for incandescent lamps, and more especially to pull sockets in which the circuit is opened and closed by a movable part actuated by pulling a chain or other flexible extension from the socket.

15 The object of the present invention is to provide a pull socket which shall be more substantial and durable and less liable to get out of order than devices heretofore in use.

20 For a more complete understanding of the invention, reference may be had to the accompanying drawing showing one embodiment of our invention, in which—

Figure 1 is a side elevation of the socket 25 without a shell; Fig. 2 is a vertical section; Fig. 3 is a view taken at right angles to Fig. 1, with parts shown in section; Fig. 4 is a detached view of the pole piece, actuating segment, and spindle; Fig. 5 is a top 30 plan view of the lower insulating base and stationary contacts; Fig. 6 is a plan of the pole piece; Fig. 7 is a perspective view of the chain bell connected to the supporting bracket; and Fig. 8 is a similar view of the 35 bell detached.

As shown in the drawing, two disks 1 and 2 of insulation, preferably of porcelain, are supported in fixed relation by metallic brackets 3, 4 and 5 which are connected by screws 40 passing through the insulating disks and engaging the bent ends of the brackets. To the lower surface of the lower disk 2 are attached a screw shell 6 for receiving the ordinary lamp base and having an inturned 45 flange resting against the surface of the disk and held thereto by screws 7 and 8 and a center contact 9 in the form of a flexible finger clamped against the lower surface of the disk 2 by a screw 10 engaging the 50 lower end of the bracket 4 which is provided with a binding screw 11 for securing one of the circuit wires. The other circuit wire is attached by means of a screw 12

carried by the bracket 5 which is connected to a stationary contact 13 through an outwardly-extending foot therefrom which is clamped between the inturned end of the bracket 5 and the upper surface of the disk 2 by the screw which secures bracket 5 to the disk.

The upper surface of the lower disk 2 has formed thereon, half way between its center and periphery, two segmental inclined surfaces 14 and 15, and between them are open spaces in which are disposed the stationary 55 contacts 13 and 16. The contacts 13 and 16 have their engaging surfaces disposed at an angle to the surface of the disk similar to the incline of surfaces 14 and 15 so that the several surfaces form a series of hills and 60 valleys. The stationary contact 16 has a foot 17 formed by an integral part extending from the inner edge, bent downwardly and outwardly and secured by the screw 8 which engages a nut and clamps the foot 65 between it and the upper surface of the disk 2, as shown in Fig. 3, and through which the contact is electrically connected to the 70 screw shell 6.

At the center of the disk 2 is formed a 75 bearing chamber 18 having a cylindrical extension 19 forming between them a shoulder on which is seated a thrust disk 20. The upper insulating disk 1 has a central 80 aperture 22 extending therethrough and enlarged to form a shoulder 23, immediately 85 below which the walls 24 are formed polygonally for a short distance, while below the walls 24 the aperture is made still larger with a cylindrical wall 25.

The spindle 26 consists of a cylindrical 90 rod with a polygonal head at its upper end. This head is pierced to receive one end of a helical spring 27 and is also provided with a transverse slot 28 for the reception of a 95 screw-driver. The lower end of the spindle 26 extends through an aperture in the thrust plate 20 while the head normally rests in engagement with the shoulder 23 in the upper disk 1 and is held from turning by the 100 polygonal walls 24.

On the spindle 26 are loosely mounted a pole piece 29 and the actuating segment 30. The pole piece consists of a disk of metal, such as brass or phosphor bronze, with segmental arms 31 punched therefrom and bent

downwardly and with ratchet shoulders 32 punched therein. In order to provide a substantial bearing for the pole piece on the spindle, the pole piece is provided with an 5 extended sleeve 33 extending through its center and swaged over at its upper end. The actuating segment consists of a triangular plate 34 provided at its center with an extended bearing sleeve 35 and on opposite 10 sides of its center with ratchet teeth 36 adapted to engage the ratchet shoulders or notches 32 of the pole piece.

Near the outer edge of the segment is attached the chain barrel 37 consisting of a 15 single piece of metal with a peripheral flange or barrel extended downwardly therefrom and a main portion overlying the triangular plate 34 and connected thereto by means of insulating disks or plates 38 20 and hollow rivets 39 extending through the insulation, the main portion of the chain barrel, and the triangular plate. This connection affords a thoroughly insulated barrel for the chain with the insulation positively clamped between metal parts so that 25 it is relieved of mechanical stresses and will not disarrange the metal parts by warping or expanding. The barrel has a key-hole slot 40 near its rear end for the reception of 30 the end link of a chain or other pull device 41, and extending downwardly from the rear end is a stop finger 42 adapted to engage shoulder projections 43 on the upper surface of the lower insulating disk 2. The 35 chain 41 overlies the outer periphery of the barrel 37 and passes out through a guide bell 44.

The guide bell is detachably connected to the bracket 3 in order that it may be removed in case of necessity, and in order to provide a rigid detachable connection the bracket 3 has a transverse lug 45 struck up from its foot and at its upper end it is formed U-shaped with a depending lug 46 45 spaced from the main portion of the bracket a certain distance. The bell is provided with a hooked finger 47 forming therewith a parallel sided recess adapted to receive the lug 45, while at its upper side the bell 50 is provided with two flexible legs 48 having out-turned feet with rounded ends adapted to be sprung in between the main portion of the bracket 3 and its upper lug 46.

It will be observed that the pole piece 29 55 is maintained in a plane at right angles to the spindle by reason of its bearing sleeve 33, and its arms 31 are positively positioned for engagement with the stationary contacts 13 and 16 upon passing beyond the inclined 60 surfaces 14 and 15, so that substantially the only friction to oppose the motion of the pole piece is that between the arms 31 and the stationary contacts or the inclined surfaces of the disk 2. It will also be observed 65 that the actuating segment is positively car-

ried in fixed relation to the pole piece by reason of its long bearing on the spindle 26, and the only friction between the actuator and the pole piece is due to the ratchet teeth 36 moving backwardly over the plane surface of the pole piece. It will further be noted that the means for adjusting the tension of the spring 27 is such that this adjustment can be accomplished by pressing slightly upon the head of the spindle 26, 70 turning it to produce the desired degree of tension, and then allowing to reseat itself under the action of the spring 27. It will also be observed that the spring 27 may be made of a wire of substantial size and of sufficient number of convolutions to provide 75 an abundance of resiliency so that danger of its becoming fatigued and broken in service is entirely avoided.

We do not desire to restrict ourselves to the particular form or arrangement of parts herein shown and described, since it is apparent that they may be changed or modified within the scope of our claims without departing from our invention.

What we claim as new and desire to secure by Letters Patent of the United States, is—

1. In a pull socket, the combination of two insulating disks, a thrust plate carried by one of said disks, a spindle supported by said disks, a rotary pole piece mounted on said spindle and having an extended bearing engaging at one end with said thrust plate, an actuating segment having an extended bearing on said spindle and ratchet means for engaging said pole piece, and a spring for retracting said actuator and urging it toward said pole piece.

2. In a pull socket, the combination of two insulating disks in one of which is formed an aperture with polygonal walls, a thrust plate carried by the other disk, a spindle having an end extending through said thrust plate and a polygonal head disposed in said aperture, a pole piece mounted on said spindle and engaging said thrust plate, an actuating segment mounted on said spindle between the pole piece and the head thereof, and a helical spring between the head of the spindle and said actuating segment operating to maintain the position of the spindle and to retract said actuating segment.

3. In a pull socket, the combination of a spindle, a pole piece, and an actuating segment comprising a metal ratchet plate for engaging said pole piece and a flanged metal chain barrel overlying said ratchet plate, and insulating rivet means whereby the last mentioned parts are secured together.

4. In a pull switch device, the combination of a bracket having a transverse lug at one end and made U shaped at the other

end, and a chain bell having at one side a transversely extended finger and at the other two spring legs.

5. In a pull switch device, the combination of a bracket having a parallel sided transverse lug at one end and made U shaped at the other end, and a detachable chain bell having at one side a transversely extended finger forming a parallel sided slot for the reception of said lug and at

the other side two spring legs with out-turned feet adapted to be sprung into the U-shaped end of said bracket.

In witness whereof, we have hereunto set our hands this 6th day of July, 1912.

HOWARD R. SARGENT.
THEODORE KOCH.
